UNITED STATES PATENT OFFICE.

JOSEPH H. LAPHAM AND OWEN T. LAPHAM, OF CLEVELAND, OHIO.

WASH-BOARD PLATE.

SPECIFICATION forming part of Letters Patent No. 357,211, dated February 8, 1887.

Application filed October 18, 1886. Serial No. 216,508. (No model.)

To all whom it may concern:

Be it known that we, JOSEPH H. LAPHAM and OWEN T. LAPHAM, of Cleveland, in the county of Cuyahoga and State of Ohio, have 5 invented a certain new and Improved Wash-Board Plate; and we do hereby declare that the following is a full, clear, and complete description thereof.

The nature of our said improvement relates 10 to the construction of said zinc plate for an effective rubbing-surface in deterging clothes or textile fabrics.

The following specification, in connection 15 with the annexed drawings, sets forth and describes in detail the construction of the said zinc plate for wash-boards.

Figure 1 is a front view of a part of the zinc plate in connection with a section of a wash-board. Fig. 2 is a sectional view of Fig. 1 in 20 the line *x x*. Fig. 3 is a detached section.

Like letters of reference refer to like parts in the several views.

This zinc plate for wash-boards is of that 25 class known as "double-faced," which admits of the plate being used for washing on one or both sides. The frame or wood part is or may be of the ordinary kind or otherwise arranged to secure the said plates in connection with the frame.

Sufficient of the entire plate is shown for a 30 proper understanding of the whole construction, in which the corrugations consist of angular flutes A, having plane faces on each side of the angle and extending across the width of the plate. These angular flutes alternate 35 with corrugations C, having spiral convolutions D upon their faces, as seen in Fig. 1. The convexity of the angular flute A at the front forms a concavity, B, on the opposite side, as seen in Fig. 2. The face E of the flute A presents a broader surface than the face F. The junction of these two faces forms the an-

gle of the flute and unites with the convolutions D in the corrugations C. These convolutions cross the corrugations diagonally with a twist 45 or curve, as seen in Figs. 1 and 3. It is preferred that these spiral-like convolutions D should run in opposite directions from the sides of the wash-board to the center G, as indicated in Fig. 1, at which point the two curving directions of the convolutions D meet. This changing of the curving directions may be made to occur at one or more parts of the zinc plate, or the same direction may be continued entirely across the plate. The swell or projections H on one side form depressions or concavities I on the other, and the depressions J between the convolutions shape projections on the opposite side of the plate. By this construction the angular flutes alternate with the 55 convoluted corrugations. The depressions on one side of the plate form projections on the other, making a double-faced zinc plate.

The parts K represent the wood sides or legs; L M, the cross-pieces connected with the 60 sides and plate, and N the soap-recess formed by the partition attached to the cross and side pieces.

What we claim as our invention, and desire 65 to secure by Letters Patent, is—

In combination with a wash-board, a double-faced zinc plate holding flutes with angular faces, and alternating corrugations having convolutions therein arranged in a curved and diagonal direction relative to the said flutes 70 and corrugations, substantially as described, and for the purpose set forth.

In testimony whereof we affix our signatures in presence of two witnesses.

JOSEPH H. LAPHAM.
OWEN T. LAPHAM.
